CLAIM

The ornamental design for a tissue box, as shown and described.

DESCRIPTION

FIG. 1 is a top, perspective view of a tissue box;

FIG. 2 is a top view thereof;

FIG. 3 is a left view thereof;

FIG. 4 is a right view thereof;

FIG. 5 is a top, perspective-view thereof with a cover removed;

FIG. 6 is a top view thereof;

FIG. 7 is a left view thereof; and,

FIG. 8 is a right view thereof.

The broken lines illustrate environmental structure and form no part of the claimed design.

1 Claim, 8 Drawing Sheets
